UNITED STATES PATENT OFFICE.

CLINTON GUYER, OF MUNCY, PENNSYLVANIA, ASSIGNOR OF ONE-HALF TO
WILLIAM C. CRAWFORD, OF MUNCY, PENNSYLVANIA.

ROTARY ENGINE.

SPECIFICATION forming part of Letters Patent No. 746,501, dated December 8, 1903.

Application filed May 29, 1903. Serial No. 159,272. (No model.)

To all whom it may concern:

Be it known that I, CLINTON GUYER, a citizen of the United States, and a resident of Muncy, in the county of Lycoming and State 5 of Pennsylvania, have invented a new and Improved Rotary Engine, of which the following is a full, clear, and exact description.

The object of the invention is to provide a new and improved rotary engine which is 10 simple and durable in construction and arranged to utilize the motive agent very economically and expansively to the fullest advantage.

The invention consists of novel features 15 and parts and combinations of the same, as will be more fully described hereinafter and then pointed out in the claims.

A practical embodiment of the invention is represented in the accompanying drawings, 20 forming a part of this specification, in which similar characters of reference indicate corresponding parts in all the views.

Figure 1 is a longitudinal central section of the improvement. Fig. 2 is a transverse 25 section of the same. Fig. 3 is a similar view of the same, showing the oscillating-valve in a different position. Fig. 4 is a perspective view of the piston; and Fig. 5 is an enlarged sectional perspective view of the abutment- 30 chamber, the abutment, and a part of the piston.

In the cylinder-heads A' and A² of the cylinder A is journaled the main shaft B, carrying at one outer end a pulley C or the like 35 for transmitting the developed power of the engine to other machinery. On the inside of the cylinder-head A' is formed or secured a hub A³, through which extends loosely the main shaft B, and the end of the hub 40 A³ terminates a short distance from the cylinder-head A², and the peripheral face of the said hub A³ is concentric to the inner surface of the cylinder A, so that the hub forms, with the cylinder, an annular working 45 chamber A⁴, as plainly shown in the drawings. In this annular working chamber travel one or more piston-heads D and D', preferably two in number, located diametrically opposite each other, as plainly indicated in Fig. 50 2, and the said piston-heads D and D' connect at one end with a ring D², fitting the

hub A³ adjacent to the head A', and the other ends of the said piston-heads D and D' are integrally connected with a disk D³, keyed or otherwise secured to the shaft B and extending in the space between the hub A³ and the cylinder-head A². It is understood that the disk D³, the ring D², and the piston-heads D and D' form the piston of the engine, the piston-heads D D' being pressed on by the motive agent, as hereinafter more fully described, so as to rotate the piston, and with it the shaft B, in the direction of the arrow a'. (Indicated in Figs. 2 and 3.)

From the bottom of the annular working 65 chamber A⁴ leads an exhaust E, and into the top of the said working chamber is adapted to swing an abutment F, fulcrumed at F' in an abutment-chamber A⁵, opening into the annular working chamber A⁴, as plainly indicated in Figs. 2 and 3. The free end of the abutment F normally rests on the peripheral face of the fixed hub A³, and the said free end of the abutment is adapted to be engaged by the peripheral cam-surface of the piston-head D or D', so as to swing the abutment F upward back into the abutment-chamber A⁵ whenever the piston-head D or D' passes the abutment from the rear to the front side thereof.

Into the top of the abutment-chamber A⁵ open ports a and b, leading from the interior of the casing G of the admission and cut-off valve for the engine, said casing G being connected with a boiler or other suitable source 85 of motive-agent supply, and in the said casing is mounted to oscillate a valve G', having its stem G² provided with an arm H, connected by an arm H' with the free end of the eccentric-rod I' of an eccentric I, secured on 90 the main shaft B. (See Fig. 1.) Now when the engine is in operation then the eccentric I by its rod I' and arms H and H' imparts a rocking motion to the valve G', so as to alternately open and close the ports a and b to 95 intermittently feed steam or other motive agent into the abutment-chamber A⁵ and from the latter by way of ports or passages F² in the said abutment into the working chamber A⁴ for the motive agent to act on the piston-head D or D' as soon as the latter has passed the abutment.

It is understood that the abutment F fits in between the ring D² and the disk D³; as plainly shown in Figs. 1 and 5, so that the motive agent passing through the ports or 5 passages F² readily fills the working chamber A⁴ and acts on the corresponding piston-head D or D' to turn the piston, and with it the shaft B, in the direction of the arrow a'.

In order to prevent leakage of steam at the 10 time a piston-head D or D' passes under the abutment F, a packing bar or block J is provided, mounted to slide radially in the upper portion of the hub A³, and this packing-bar J is held normally in an uppermost position 15 by a spring J' and is prevented from shifting transversely by a suitable cross-bar J², held in a recess in the front face of the hub A³. (See Figs. 2 and 3.) Now this packing-bar J engages the inner face of the ring D² as 20 well as the under side of the piston-head D or D' as the latter moves along under the abutment F, so that leakage of steam to the rear of the piston-head is prevented at the time a piston-head passes under the abut- 25 ment.

The operation is as follows: When a piston-head D or D' has passed the abutment F, (see Fig. 3,) then the valve G' uncovers either 30 of the ports a or b, so that the motive agent can now pass from the casing G through the abutment-chamber A⁵ and the abutment F into the working chamber A⁴ to act on the corresponding piston-head D or D' to turn the piston and the shaft in the direction of the 35 arrow a'. As soon as the piston-head D or D' has advanced a desired distance then the valve G' closes the corresponding port a or b, so as to shut off the motive agent from the working chamber, and hence the steam con- 40 fined in the working chamber now works expansively and finally passes from the working chamber into the exhaust E as soon as the piston-head D or D' has passed the said exhaust. When this takes place, the other piston-head, now at the top, moves past the abutment F, as previously described, and when 45 this takes place the other port b or a opens, so that the motive agent is again admitted to the working chamber to act on the second pis- 50 ton-head, and the above-described operation is then repeated.

From the foregoing it will be seen that the steam is cut off during a desired portion of the stroke of the piston—that is, during its 55 passage from the abutment to the exhaust E—to allow the steam to work expansively. As the steam-pressure is equal on the ring D² and the disk D³, the piston is completely balanced, and hence the engine runs easily with- 60 out undue loss of power and without waste of steam. As the engine is composed of com- paratively few parts, it is not liable to easily get out of order.

In order to reduce the weight of the engine, 65 the hub A³ may be formed with openings or a spider-web.

Having thus described my invention, I

claim as new and desire to secure by Letters Patent—

1. A rotary engine comprising a cylinder 70 having an annular working chamber, a piston mounted to travel in the said annular working chamber and consisting of a ring, a disk and a piston-head connecting the ring with the disk and having a peripheral cam- 75 face, a swinging abutment mounted to swing into the said annular working chamber and adapted to be engaged by the cam-face of the piston-head, to swing the abutment outward for the passage of the piston-head, and an 80 admission and cut-off valve for intermittently feeding the motive agent to the annular working chamber, as set forth.

2. A rotary engine comprising a cylinder 85 having an annular working chamber, a pis- ton mounted to travel in the said annular working chamber and consisting of a ring, a disk and a piston-head connecting the ring with the disk and having a peripheral cam- 90 face, a swinging abutment mounted to swing into the said annular working chamber and adapted to be engaged by the cam-face of the piston-head, to swing the abutment outward for the passage of the piston-head, and an 95 admission and cut-off valve for intermittently feeding the motive agent to the annular working chamber, by way of ports in the said abut- ment, as set forth.

3. A rotary engine comprising a cylinder, a central cylindrical hub secured to one cylin- 100 der-head and projecting to within a distance of the other cylinder-head, to form with the cylinder an annular working chamber, a main shaft journaled in the cylinder-heads and ex- 105 tending through the said hub, a piston com- prising a ring extending around the hub, a disk extending in the space between the end of the hub and the adjacent cylinder-head, the disk being secured to the said main shaft, and one or more piston-heads, for connecting 110 the said ring with the said disk, the piston- head traveling in the said working chamber and having a peripheral cam-face, and a piv- oted abutment adapted to swing in and out of the said working chamber, between the 115 piston-ring and piston-disk, the free end of the abutment normally resting on the said hub and the piston-head being adapted to be 120 swung outward by the cam-surface of the piston-head, as set forth.

4. A rotary engine comprising a cylinder, a central cylindrical hub secured to one cylin- 125 der-head and projecting to within a distance of the other cylinder-head, to form with the cylinder an annular working chamber, a main shaft journaled in the cylinder-heads and ex- 130 tending through the said hub, a piston com- prising a ring extending around the hub, a disk extending in the space between the end of the hub and the adjacent cylinder-head, the disk being secured to the said main shaft, and one or more piston-heads, for connecting 135 the said ring with the said disk, the piston- head traveling in the said working chamber

and having a peripheral cam-face, a pivoted abutment adapted to swing in and out of the said working chamber, between the piston-ring and piston-disk, the free end of the abutment normally resting on the said hub and the piston-head being adapted to be swung outward by the cam-surface of the piston-head, an admission and cut-off valve for intermittently feeding the motive agent to the working chamber by way of the said abutment, and means actuating the said valve from the said main shaft, as set forth.

5. A rotary engine comprising a cylinder, a central cylindrical hub secured to one cylinder-head and projecting to within a distance of the other cylinder-head, to form with the cylinder an annular working chamber, a main shaft journaled in the cylinder-heads and extending through the said hub, a piston comprising a ring extending around the hub, a disk extending in the space between the end of the hub and the adjacent cylinder-head, the disk being secured to the said main shaft, and one or more piston-heads, for connecting the said ring with the said disk, the piston-

head traveling in the said working chamber and having a peripheral cam-face, a pivoted abutment adapted to swing in and out of the said working chamber, between the piston-ring and piston-disk, the free end of the abutment normally resting on the said hub and the piston-head being adapted to be swung outward by the cam-surface of the piston-head, an admission and cut-off valve for intermittently feeding the motive agent to the working chamber by way of the said abutment, means actuating the said valve from the said main shaft, and a spring-pressed packing-bar in the said hub, under the said abutment, to engage the under side of a piston-head at the time the latter swings the abutment outward, as set forth.

In testimony whereof I have signed my name to this specification in the presence of two subscribing witnesses.

CLINTON GUYER.
